UNITED STATES PATENT OFFICE.

FRED L. MAYTAG, OF NEWTON, IOWA.

DEFLOODER FOR INTERNAL-COMBUSTION ENGINES.

1,342,558.

Specification of Letters Patent.

Patented June 8, 1920.

Application filed May 31, 1917. Serial No. 171,971.

To all whom it may concern:

Be it known that I, FRED L. MAYTAG, a citizen of the United States, residing at Newton, in the county of Jasper and State 5 of Iowa, have invented certain new and useful Improvements in Deflooders for Internal-Combustion Engines, of which the following is a specification.

This invention relates to deflooders for internal combustion engines, and particularly to an extremely simple, efficacious and economical device for draining the condensed fuel from the crank case.

A difficult problem to solve in perfecting 15 the two-cycle engine has been to provide a device to drain the condensed fuel from the crank case in a satisfactory manner.

It is a well known fact that with the present grade of gasolene for fuel, there is 20 a certain amount of the mixture that comes in contact with the walls of the passages and becomes condensed before it can be delivered to the combustion end of the cylinder. When this condensed fuel accumulates 25 in the crank case of a two cycle engine, it causes the engine to lose its power and often causes it to stop because this unmixed fuel is picked up by the mixed fuel going to the cylinder. This makes the charge too 30 rich to explode readily, and to overcome this defect this improvement has been devised.

One of the objects of this invention is to provide a device that will in a practical 35 manner drain the crank case of condensed fuel without excessive loss of pressure.

It is a further object of this invention to provide a float to ride on the fuel in the supply reservoir to prevent the fuel being drawn 40 up through the deflooding opening.

A further object of this invention is to provide an indicator to show the amount of fuel in the reservoir or supply tank.

Other objects and advantages will appear 45 as the following description proceeds.

In the accompanying drawings, I have illustrated a preferred embodiment of my invention. However, I wish it to be understood that it is capable of modifications and 50 changes without departing from the spirit of the invention, except as limited by the appended claims.

In the drawings:

Figure 1 is a side elevation of an internal 55 combustion engine embodying my invention,

parts being broken away to show my new deflooder and float.

Fig. 2 is an enlarged transverse vertical sectional view of my new deflooder.

In the drawings, 1 represents generally 60 the fuel tank or reservoir, upon which is mounted the crank case 2. The cylinder 3 carries the piston 4. Located in the lower portion of the crank case is an aperture 5, which opens between the crank case and the 65 fuel tank. In the fuel tank is a float 6, which rides upon the fuel contained therein, and to which float is attached a gage wire 7, which passes through a suitable opening 8 in the upper portion of the fuel tank and out- 70 side of the crank case. This wire or rod 7 projects above this upper portion of the fuel tank, and serves as an indicator as to the amount of fuel in the tank.

The aperture 5 opening between the crank 75 case and the fuel tank is of tapered formation, it constricting at its upper end, and enlarging at its lower end. This aperture 5 may be formed directly in the metal of the bottom of the crank case if desired, or for 80 convenience of manufacture, cleaning, replacement, etc., it may be formed of the proper shape and size in a nipple 9 screwed in the bottom of the crank case. This nipple 9, shown in the enlarged Fig. 2, is provided 85 with threads 10 and the head 11, whereby it may be screwed into a hole provided therefor through the bottom of the crank case and easily removed therefrom for cleaning or replacement. As is shown in Fig. 1, the 90 rounded upper end 12 of this nipple extends slightly above the bottom of the crank case.

In a four cylinder engine the fuel that condenses in the cylinder leaks past the rings of the piston then down to the crank 95 case, and finally into the lubricating oil; but in the two cycle type of gas engine, the condensed fuel settles to the bottom of the crank case, and consequently destroys the even flow of combustible mixture. With my 100 improved deflooder, this difficulty in the two cycle engine is eliminated for the reason that the condensed fuel is effectively drained away without excessive loss of pressure.

When the piston 4 rises in the cylinder 3, the mixture of fuel and air is drawn into the crank case 2. When the piston makes the down stroke, the mixture is transferred to the combustion end of the cylinder, and 110

any condensed fuel, oil, etc., that may have collected in the bottom of the crank case are blown out through the opening 5, and thus conducted back into the fuel reservoir.

- 5 By the provision of the float 6, which rides upon the fuel in the fuel tank, the fuel is prevented from being drawn up through the defflooding opening 5 by virtue of the fact that the float is directly below the 10 opening and hence before any fuel could be thus drawn up it would have to be drawn from beyond the edges of the float which would not occur owing to the greatness of the distance. The rod 7 carried by the float 15 and extending a suitable distance above the opening 8, provides an effective indicator to show the amount of fuel in the reservoir.

In Fig. 1 the section is taken through the bottom of the crank case, but the carbureter which is positioned outside of the 20 crank case is shown merely to more clearly illustrate the relation of the parts. The float 6 and the carbureter pipe leading downwardly into the fuel tank are so arranged that the float is capable of up and 25 down movement.

Having now described my invention, I claim:

1. In apparatus of the class described a 30 crank case, a fuel reservoir beneath said case, the bottom of said crank case having a free unobstructed opening therethrough communicating with said reservoir, said opening being tapering with its small end at 35 the top whereby any liquid collected in the crank case will be blown through the opening without excessive loss of pressure.
2. In apparatus of the class described a 40 crank case, a fuel reservoir beneath said case, the bottom of said crank case having an opening therein directly connecting said case and said reservoir, a nipple removably

secured in said opening, said nipple having a tapered opening therethrough the small end of said tapered opening being at the top 45 of the nipple and of small diameter whereby any liquids such as fuel, oil, or the like that may have collected in the bottom of the casing will be blown through said nipple into the reservoir without excessive loss of 50 pressure in the crank case and whereby the opening may be readily cleaned by first removing the nipple, in the event that the opening in the nipple should become clogged.

3. In apparatus of the class described a fuel reservoir, a crank case mounted above said reservoir, a tapered opening directly connecting said case and said reservoir for defflooding purposes, the small end of said 60 opening being up and of small diameter, and a float in said reservoir directly below said opening to decrease the possibility of any fuel being drawn from said reservoir upwardly through said opening.

4. In apparatus of the class described a reservoir, a crank case mounted above said reservoir, a tapered opening directly connecting said case and said reservoir for defflooding purposes, the small end of said 70 opening being up and of small diameter, a float in said reservoir directly below said opening to decrease the possibility of any fuel being drawn from said reservoir upwardly through said opening, and a wire 75 extending from said float upwardly to serve as a gage as to the contents of said reservoir.

In witness whereof, I hereunto subscribe my name to this specification in the presence of two witnesses.

FRED L. MAYTAG.
